W. McKibbin.

Truss Bridge.

N° 19,573.

Patented Mar. 9, 1858.

UNITED STATES PATENT OFFICE.

W. MCKIBBIN, OF SAN FRANCISCO, CALIFORNIA.

CONSTRUCTING FRAMING OF BRIDGES, &c.

Specification of Letters Patent No. 19,573, dated March 9, 1858.

To all whom it may concern:

Be it known that I, WILLIAM MCKIBBIN, of the city of San Francisco, in the county of San Francisco and State of California, have invented a new and useful Method of Combining Metal Bars and Plates to be Used in the Construction of Bridges and other Structures; and I do hereby declare that the following is a full, clear, and exact description of the same, reference being had to the accompanying drawings, making a part of this specification, in which—

Figures 1 and 2 are elevations of opposite sides of one panel of an iron bridge-girder, in which my invention is applied. Fig. 3 is a transverse vertical section of the same, in the line x, x , of Figs. 1 and 2. Fig. 4 is a horizontal section in line y, y , of Fig. 1. Figs. 5 and 6, are detail views.

Similar letters of reference indicate corresponding parts in all the figures.

This invention consists in a novel and very simple method of clamping and securing together the ends of metal bars and of uniting plates with the said bars, by which great strength is obtained.

The invention is applicable in almost all cases where it is required to connect the ends of iron bars whether or not it is required to combine plates with the said bars.

To enable others to make and use my invention, I will proceed to describe its construction and operation.

A, A, are a series of flat iron bars arranged edgewise one above the other and united to form part of the bridge girder. B is a plate iron sheathing, covering one side of the said series of bars. As the bars A, A, extend the whole length of the bridge, each has to be composed of several lengths or sections united at their ends; and the mode in which these lengths or sections are united and combined with the sheathing plate constitutes my invention.

The ends of two lengths which are to be connected are bent at right angles to the length of the bar to form lugs a, a , as shown in Figs. 4 and 5, and narrow slots are cut through the ends as shown at b, b , in Fig.

5, to receive a wedge or taper key c . Between the lugs a, a , of the two lengths of bar iron A, A, is fitted a plate C, of which a separate view is given in Fig. 6, and which is also shown in Figs. 1, 2, 3, 4, and whose width is the same as the width of the bars A, A, the said plate containing a long slot d , of a proper width to receive the wedge or key c . A plate D, (or piece of iron similar to that of which the bars A, A, is composed,) is placed against the opposite side of the joint to that on which the lugs a, a , project, and this plate D is slotted for the plate C, to pass through it. When the plate C is placed between the lugs a, a , and the plate D, applied, the wedge or key c , is inserted through the slots b, b , and d , of the lugs and plate C, and a wedge e , is inserted in the slot d , outside of the plate D, and when both wedges are driven tight, the joint between the two lengths of bars A, A, is secure. The sheathing B, when used is simply applied close to the bars A, A, on either side, holes being provided in the sheathing for the plates C, C, or for said plates and lugs a, a , to pass through, according to which side of the bars the sheathing is required. When a series of several bars are to be combined by arranging them together edgewise, as shown in Figs. 1, 2, and 3, the plates D, D, are intended to be long enough to lie across the whole series or several of said bars, and to serve for two joints, as shown in Figs. 1 and 2; but if a single line of bars only are intended to be united, these plates need only be long enough to cover one joint.

What I claim as my invention, and desire to secure by Letters-Patent, is:

The combination of the slotted lugs a, a , on the ends of the bars, the slotted plates C, and D, and the wedges or keys c, e , substantially as described, for the purpose set forth.

WM. MCKIBBIN.
